142,219

DESIGN FOR A HEATER OR THE LIKE

Caryl A. Lindberg, Glendale, and Howard W. Eckles, St. Louis, Mo., assignors to The Emerson Electric Manufacturing Company, St. Louis, Mo., a corporation of Missouri

Application December 20, 1944, Serial No. 117,006

Term of patent 14 years

(Cl. D81—10)

To all whom it may concern:

Be it known that the undersigned, Caryl A. Lindberg and Howard W. Eckles, both citizens of the United States, residing at Glendale, St. Louis County, Missouri, and St. Louis, Missouri, respectively, have invented a new, original, and ornamental Design for Heater or the like, of which the following is a specification, reference being had to the accompanying drawing forming a part thereof, in which:

Fig. 1 is a front view of the heater, showing our new design;

Fig. 2 is a side view thereof, the opposite side being the same; and

Fig. 3 is a rear view thereof.

The dominant features of our design reside in the portions shown in full lines in each of the several views.

We claim:

The ornamental design for a heater or the like, substantially as shown and described.

CARYL A. LINDBERG.
HOWARD W. ECKLES.
